UNITED STATES PATENT OFFICE.

ANDREW B. HYDE, OF NEW YORK, N. Y.

FOUNTAIN PEN.

Application filed February 5, 1921. Serial No. 442,600.

To all whom it may concern:

Be it known that I, ANDREW B. HYDE, a citizen of the United States, residing in the borough of Manhattan, city, county, and 5 State of New York, have invented an Improvement in Fountain Pens, of which the following is a specification.

This invention relates to a fountain pen and more particularly to that type of fountain pen in which there is employed a reservoir to receive and hold an overflow or surplus of ink in order to prevent the ink from dropping from the pen and causing blots. I am aware that heretofore fountain pens 10 have been provided with an excess or overflow ink reservoir and that in such structures there has been provided a wall enclosing the reservoir chamber beneath the pen. These structures, however, have proved unsatisfactory because no adequate provision has been 15 made for preventing the action of gravity from overcoming the adhesion of the overflow ink to the under surface of the pen and feeder and to the wall of the overflow reservoir. The result is that often the overflow 20 ink escapes from the overflow reservoir through the space existing between the pen and the edges, and sides of the wall enclosing the chamber of the overflow reservoir 25 and makes a blot.

The object of my invention is to overcome this difficulty and in doing so I provide a means of preventing the action of gravitation from causing the ink to pass from the 30 overflow reservoir and drop from the pen, thereby making a blot. In carrying out the invention to obtain the desired result I employ an overflow reservoir provided with a cover closing or substantially closing the 35 same and conforming substantially to the inner or under surface of the pen. The surfaces of the cover co-act with the surface of the feeder, the under surface of the pen and the inner surface of the walls of the reservoir, thereby furnishing a sufficient amount 40 of surface to provide for adhesive action great enough to prevent the ink in the overflow reservoir from passing out therefrom and dropping from the pen. The cover 45 member furthermore is provided with an opening, parts of which lie on both sides of the feeder beneath the nibs of the pen so as to permit the flow of ink from the feeder to the overflow reservoir when the ink flows 50 too freely from the main reservoir of the pen and also to permit the ink to flow from the

overflow reservoir in the opposite direction to the nibs of the pen to supply the same with ink and clear the overflow of ink, when the overflow of ink from the feeder has 55 ceased.

The fountain pen made in accordance with my invention preferably comprises a cylindrical or barrel member containing the main ink reservoir and a pen section is connected thereto and comprises a nozzle, a plug fitted in the nozzle and with which there is associated a pen, a feeder and suitable walls forming an overflow reservoir and including a cover with an opening therein to which reference has hereinbefore been made and all of which will be hereinafter more particularly described.

In the drawing;

Fig. 1 is a central longitudinal cross section of a fountain pen made in accordance 75 with my invention.

Fig. 2 is an enlarged cross section on line 2—2, Fig. 1.

Fig. 3 is a plan view of the cover of the 80 overflow reservoir.

Fig. 4 is a similar view showing the feed member associated with the cover of the reservoir.

Fig. 5 is a side elevation of the parts illustrated in Fig. 4, and

Fig. 6 is a longitudinal section illustrating the cap employed with the pen.

Referring to the drawing it will be seen that the fountain pen made in accordance 90 with this invention comprises a cylindrical or barrel member 10. This, as is customary, is fitted with a pen section which includes a nozzle 11 connected to the end of the barrel by screw threads 12 in the usual manner. 95 The pen section also includes a plug 13, a pen 14, a cover 18 and a feeder 21, which are secured to the nozzle 11 by frictional contact. The overflow reservoir is indicated at 15 and the walls 16 thereof are connected to or made integral with the plug member and in a suitable position are provided with a slot 17, the purpose of which will be hereinafter indicated.

The reservoir also is provided with a cover 18 which is made to fit the said walls so as to close or substantially close the reservoir, and the upper surface of the cover is made to conform generally to the inner surface of the pen. At or adjacent to its outer end 105 the cover is provided with a hole or opening 19 and in the upper surface of the cover ex-

tending longitudinally of the same there is a groove 20 to receive the feeder 21 in which there is also a longitudinal groove 22 through which the ink passes from the reservoir 10' in the cylindrical or barrel member of the pen. As is customary the plug 13 is provided with a vent or passage 23 and as illustrated in the drawing the cover may be secured in position upon the plug and upon 10 the edges of the reservoir walls by suitable pins 24, 25 or otherwise. As will be also noted in the drawing the cover 18 at its outer end preferably fits and lies within the end portion of the walls forming the overflow reservoir as is also the case with the feeder 21 and in addition to the pins 24 and 25 the cover may be suitably connected to the walls of the reservoir by being cemented 15 or otherwise connected thereto. When there is ink in the overflow reservoir 15, and the fountain pen is lying in a horizontal position or held in a perpendicular position in the pocket, such ink may ooze out through the point of contact of the cover 18 with the 20 edge of the reservoir wall and thus soil both the cap 26 and the nozzle 11. By cementing the cover 18 to the edge of the reservoir wall, the point of contact is made impervious to the passage of ink; and the soiling of the 25 cap and nozzle is thereby prevented.

In the use of the pen, as hereinbefore described, the ink from the main reservoir 10', as is customary, flows therefrom through the feeder to the pen where it may be used. In the event of the ink flowing too freely the surplus ink, as will be understood, passes through the hole 19 into the overflow reservoir, and the hole 19 made in the cover for this purpose is preferably as narrow as is 30 compatible with the efficient operation of the pen. This hole, however, may be of any desired length. The air necessary to replace the ink as withdrawn from the main reservoir 10' passes through the slot 17 into the overflow ink reservoir 15 and through the 35 vent 23 to the main reservoir and when the ink flows too freely the surplus passes through the opening 19 in the cover 18 to the overflow reservoir 15. This overflow 40 ink adheres to the walls of the overflow reservoir, to the inner surface of the cover 18, to the outer surface of the cover 18, to the outer surface of the feeder 21, and to the under surface of the pen 14; and these adhesions are sufficient to prevent the action of 45 gravity from drawing the ink out of the overflow reservoir and making a blot. Likewise when the overflow of ink from the feeder 21 has ceased, the ink in the overflow reservoir 50 passes in the opposite direction through the opening 19 in the cover 18 to the nibs of the pen 14 in order to supply the pen with ink for writing and clear the overflow reservoir of surplus ink. Manifestly also any ink 55 which passes through the vent 23 in the plug

is contained in the overflow reservoir and may pass from the same through the opening 19 to supply the pen with ink, in which case the overflow reservoir is cleared of this ink in the same manner as the surplus ink 60 from the feeder is taken care of.

While I have shown and described the feeder as associated with the outer surface of the cover of the reservoir it will be understood that this member may be otherwise 65 disposed and the pen made to operate to equally good advantage. For example, the feeder member may be made an integral part of the cover, or the feeder may be caused to pass through the cover, or the feeder might 70 be made to lie on the inner side of the cover without departing from the nature and spirit of the invention.

By reference to Fig. 6 it will be seen that 75 the pen may be provided with a cap indicated at 26 and adapted to be connected by suitable screw threads or otherwise with the nozzle 11 so as to cover the pen section when the pen is not in use.

I claim as my invention:

1. In a fountain pen, a pen section comprising a pen, a plug having an ink reservoir therein, and a feeder member extending beneath the pen and across an opening in the wall of the reservoir to provide a passage 95 for surplus ink from the feeder to the reservoir and also for the flow of the ink from the reservoir to the pen.

2. In a fountain pen, a pen section comprising a pen, a plug having a reservoir 100 therein, and a feeder member extending centrally across an opening in the outer end of the wall of the reservoir beneath the nibs of the pen to provide passages on either side of the feeder member for the flow of surplus 105 ink from the feeder to the reservoir and also for the flow of the ink from the reservoir to the nibs of the pen.

3. In a fountain pen, a pen section comprising a pen, a plug having an ink reservoir 110 therein, a cover enclosing the reservoir and lying beneath the said pen and having an opening therein at the outer end thereof lying beneath the nibs of the pen, and a feeder member associated with the cover 115 and adapted to cross the said opening therein to provide passages on either side of the end of the feeder member for the flow of surplus ink to the reservoir and also to permit ink from the reservoir to flow there- 120 from to the nibs of the pen.

4. In a fountain pen, a section comprising a plug, a pen, an overflow ink reservoir, the walls of which are connected to the said plug, a cover for the reservoir conforming 125 to the inner surface of the pen and having an opening therein lying beneath the nibs of the pen, and a feeder having a longitudinal groove therein lying within a groove provided therefor in the said cover so that 130

- the feeder is interposed between the said pen and the cover of the reservoir.
5. In a fountain pen, a section comprising a plug having a vent therein, a pen, an over-flow ink reservoir, the walls of which are connected to the said plug, a cover enclosing the reservoir and in its upper surface conforming to the inner surface of the pen and having an opening therein lying beneath the 10 nibs of the pen, and a feeder extending through the said plug and having a longitudinal groove therein, the said feeder lying in a groove provided therefor in the upper surface of the cover so as to be interposed 15 between the cover and the said pen.
6. In a fountain pen, a section comprising a plug, a pen, an overflow ink reservoir, the walls of which are connected to the said plug and are provided with an air opening, a 20 cover for the reservoir conforming to the inner surface of the pen and having an opening therein beneath the nibs of the pen, and
- a feeder having a longitudinal groove therein lying within a groove provided therefor in the said cover so that the feeder 25 is interposed between the cover and the said pen.
7. In a fountain pen, a section comprising a plug having a vent therein, a pen, an over-flow ink reservoir, the walls of which are 30 connected to the said plug and are provided with an air opening, a cover enclosing the reservoir and in its upper surface conforming to the inner surface of the pen and having an opening therein lying beneath the 35 nibs of the pen, and a feeder extending through the said plug and having a longitudinal groove therein, the said feeder lying in a groove provided therefor in the upper surface of the cover so as to be interposed 40 between the cover and the said pen.

Signed by me this 18th day of January, 1921.

ANDREW B. HYDE.
